UNITED STATES PATENT OFFICE.

CLIFFORD R. CLARK, OF NEW HAVEN, CONNECTICUT, ASSIGNOR OF ONE-HALF TO
FREEMAN P. CLARK, OF NEW HAVEN, CONNECTICUT.

AUTOMATIC GAS-BURNER.

1,070,016.

Specification of Letters Patent. Patented Aug. 12, 1913.

Application filed April 5, 1913. Serial No. 759,163.

To all whom it may concern:

Be it known that I, CLIFFORD R. CLARK, a citizen of the United States, residing at New Haven, in the county of New Haven and 5 State of Connecticut, have invented a new and useful Improvement in Automatic Gas-Burners; and I do hereby declare the following, when taken in connection with the accompanying drawings and the characters of 10 reference marked thereon, to be a full, clear, and exact description of the same, and which said drawings constitute part of this application, and represent, in—

Figure 1 a front view of a burner constructed in accordance with my invention. Fig. 2 a similar view with the cap and valve removed. Fig. 3 a view in vertical section showing the burner in the closed position. Fig. 4 a similar view showing the burner in 20 the open position. Fig. 5 a front view of the valve detached. Fig. 6 a plan view of the valve spring.

This invention relates to an improvement in automatic gas burners, that is, burners 25 which when extinguished without turning off the supply of gas will automatically close the valve to prevent the escape of gas, the object being a simple arrangement of parts which will work automatically; and 30 the invention consists in the construction hereinafter described and particularly recited in the claim.

In carrying out my invention, I employ a circular body 2 formed at its lower end with 35 an internally threaded stem 3 adapted to be turned onto the nipple of the gas-supply pipe not shown. The upper end 4 is externally threaded to receive a burner tip 5 of any approved construction. The body 2 is provided with a substantially centrally 40 arranged wall 6, and one side is closed by a plate 7 forming a gas-passage 8. The other side is closed by a cap 9 which is preferably bowed outward, this cap being 45 held in place by being threaded into the central opening of the body. Connected with the cap is a flexible diaphragm 10. In the cap is an opening 11 closed by a plug 12 through which opening ether or other material having a low boiling point may be 50 introduced, the opening being afterward sealed by the plug 12. In the wall 2 are ports 13 which are closed by a flat valve 14 the stem 15 of which passes through a hole 55 16 formed for it in the plate. The other end

of the stem has an arm 17 attached to it, and this arm bears upon a bowed spring 18 which has a clearance slot 19 for the stem 15, the ends of the spring bearing against the outer face of the wall 6, the tendency of 60 the spring being to draw the valve 14 against the inner face of the wall 6 and so as to close the ports 13. The supply of gas entering the burner enters the passage 8 between the inner wall 6 and the plate 7 and 65 escapes to the burner from the space between the outer face of the wall 6 and the diaphragm 10. Secured to the outer face of the cap 9 is a conductor bar 20 the upper 70 end of which stands adjacent to the burner tip 21. In the normal condition the diaphragm will be bowed outward so as to stand substantially parallel with the cap 9, and preparatory to lighting the gas heat will be applied to the cap by holding a 75 match close to the lower end of the conductor 20, but comparatively little heat will be required to expand the ether between the cap and diaphragm so as to cause the diaphragm to move rearward, and pressing 80 against the arm 17 force the valve 14 away from the wall 6 so as to open the ports 13. The gas may then freely pass to the burner tip and be ignited, and the heat from the gas will be carried by the conductor so as to 85 maintain the necessary heat on the cap to keep the ether expanded and thus the burner will remain open. If, however, the light should be accidentally extinguished, or 90 extinguished without turning off the source of supply, the ether will rapidly cool allowing the diaphragm to move forward and permit the spring 18 to force the valve 14 into its closed position, thus cutting off the flow of gas to the burner tip. 95

I claim:

A burner comprising a central portion adapted to be attached to a supply pipe, a burner tip applied to the upper end of the body, a vertically arranged wall in the body, 100 a passage from the bottom opening to one side of the wall and a passage to the burner at the opposite side of the said wall, ports in said wall, a plate connected with the rear of the body and forming a passage between 105 the plate and wall, a cap connected with the front of the body and forming a chamber between it and the front face of said wall, a diaphragm connected with said cap and forming a chamber between them, a valve 110

between the wall and plate and adapted to close ports in the wall, said valve formed with a stem extending through the wall, an arm connected with the said stem, a spring between the stem and outer face of the wall, said spring normally tending to hold the valve in a closed position, a conductor connected with said cap and extending upward to a point adjacent to the burner tip, and an expansive fluid between the cap and dia-

phragm adapted when heated to expand the diaphragm and open said valve.

In testimony whereof, I have signed this specification in the presence of two subscribing witnesses.

CLIFFORD R. CLARK.
